UNITED STATES PATENT OFFICE.

JOHN D. RUSS, OF SPENCER, WEST VIRGINIA.

SUPERHEATING MECHANISM FOR AUTOMOBILES.

1,220,563.

Specification of Letters Patent. Patented Mar. 27, 1917.

Application filed November 14, 1916. Serial No. 181,321.

To all whom it may concern:

Be it known that I, JOHN D. RUSS, a citizen of the United States, residing at Spencer, in the county of Roane and State of West Virginia, have invented certain new and useful Improvements in Superheating Mechanism for Automobiles, of which the following is a specification.

One of the more important objects of my invention is to provide novel means for keeping cool the engines of automobiles.

Another more important object of the invention is to provide means for keeping free from carbon the engines of automobiles.

Another more important object is to provide novel means for heating the low-grade gasolene, or other low-grade liquid fuels, causing rapid vaporization thereof.

Subsidiary objects will appear as the specification proceeds and the nature of the invention more fully appears.

In the accompanying drawing, I have shown, as an illustration, one form of embodiment of my inventive ideas capable of carrying out the underlying principles thereof. The different figures of the drawing may be briefly described as follows:

Figure 1 is a side elevation of an automobile engine and associated parts, showing the application of my invention thereto;

Fig. 2 is a fragmentary detail view, in central vertical section, of the superheater;

Fig. 3 is a fragmentary detail view, in side elevation, of the valve in the pipe leading from the radiator to the superheater.

Referring, now, in detail to the drawing:

1 and 2 designate, respectively, the intake and exhaust manifolds of the engine, and

3 the radiator.

The superheater comprises, preferably, a cylindrical shell or body 4 externally threaded toward one end thereof, as at 5, so that it may be screwed into, and thus be positioned

mainly within, the exhaust manifold 2, as shown in Fig. 1. The shell has an expanded base 6, having diametrically-opposite, externally-threaded side nipples 7 and 8 and an axial, externally-threaded nipple 9. The

shell is closed at the end 10 which is opposite the threaded end 5. Within the shell 4 is a concentric tube 11, the side wall of which is spaced from the side wall of the

shell 4, the end 11' of the tube being, also, spaced from the end 10 of the shell 4, and the other end being supported by, and, in

this instance, integral with, the base 6. The nipple 9 is provided with an axial bore 12 in alinement with and forming a continuation of the bore of the tube 11. The bore 12 extends through the basal portion 6. Between the tube 11 and the shell 4 is thus formed a superheating chamber 13, communicating, at one end, with the open end 11' of the tube 11 and, at its other end, with ports 13, 14 extending through the nipples 7 and 8, respectively, and through the basal portion 6.

Coupled to the nipple 9 by means of a coupling 15 is a pipe 16, the other end of which communicates with the intake-manifold, as shown in Fig. 1.

Coupled to the nipple 7 by means of a coupling 17 is a pipe 18, the other end of which is tapped into the top of the radiator 3, above the water-level therein.

Coupled to the nipple 8 by means of a coupling 19 is a pipe 20 leading from the fuel-tank (not shown).

In the pipe 18 is a valve-casing 21, in which is a valve 22 opening by suction in the engine, against the stress of a spring 23. The valve is provided with a valve-stem 24.

In operation, fuel from the tank is drawn through pipe 20 into the superheater 4, which, being inside the exhaust-manifold 2, highly heats the fuel, causing it to vaporize more rapidly. Simultaneously, by the suction in the intake, vapor or steam from the top of the radiator is drawn through pipe 18 into the superheater 4, where it is superheated. The superheated fuel and the superheated vapor are both drawn down through the tube 11 and through the pipe 16 into the intake-manifold 1.

It will be noted that, as the hot vapor is sucked out of the top of the radiator 3, as described, there will be an inrush of cold air to the radiator through the overflow pipe thereof, thus maintaining the water in the radiator cooler than it otherwise would be.

It will also be observed that, by taking the steam or vapor from the radiator, as described, and superheating it in the superheater 4, and introducing it into the engine-cylinder, this superheated steam soaks into and softens the carbon, which is blown out with the exhaust, thus keeping the engine clean.

The advantages of my invention are apparent, especially to those skilled in the art to which it pertains. The device is simple in

construction, and efficient in operation; it needs no attention when once installed; it saves oil and gasoline by running the engine cooler and keeping it clean of carbon; it needs 5 no extra water supply; it takes none of the water of the radiator until it is converted into steam; it permits superheated steam, not water, to be taken into the engine; it causes an inrush of cold air into the radiator 10 all the time the engine is running; and by its use low-grade fuels may be used.

It will be obvious, of course, that the device may be used only to superheat the fuel entering the superheater 4 through pipe 20 15 leading from the fuel-tank,—in which case, the pipe 18 would be dispensed with and the nipple 7 plugged; or it may be used only to superheat the vapor or steam drawn from the top of the radiator through the pipe 18 20 into the superheater,—in which case, the pipe 20 would be dispensed with and the nipple 8 plugged.

It will be understood that departures from the physical embodiment shown, within the 25 terms of the appended claims, may be made without departing from the spirit of the invention, and that all such changes fall within the purview of the invention.

Having thus fully described my invention, 30 what I claim as new and desire to secure by Letters-Patent of the United States is:

1. In an automobile, the combination, with the intake and exhaust manifolds of the engine, of a superheater, comprising a hollow 35 body projecting into the exhaust-manifold and closed at the end thereof interior of the exhaust-manifold, and an open-ended tube carried within said body and spaced from the side wall and said closed end thereof 40 of, forming a superheating chamber between said tube and said body communicating with the tube adjacent said closed end of the body; a radiator; a pipe communicating with said chamber and with said radiator, 45 above the water-level thereof; and a second pipe communicating with said tube and with said intake-manifold.

2. In an automobile, the combination, with the intake and exhaust manifolds of the engine, of a superheater, comprising a hollow 50 body screwed into the exhaust-manifold so as to be disposed therein, and being closed at the end thereof interior of the exhaust-manifold, and an open-ended tube carried within said body and spaced from the side wall and said closed end thereof, forming 55 a superheating chamber between said tube and said body communicating with the tube adjacent said closed end of the body; a radiator; a pipe communicating with said chamber and with said radiator, 60 above the water-level thereof; and a second pipe communicating with said tube and with said intake-manifold.

water-level thereof; and a second pipe communicating with said tube and with said intake-manifold.

3. In an automobile, the combination, 65 with the intake and exhaust manifolds of the engine, of a superheater, comprising a hollow body projecting into the exhaust-manifold and closed at the end thereof interior of the exhaust-manifold, and an open-ended tube carried within said body and spaced from the side wall and said closed end thereof, forming a superheating chamber between said tube and said body communicating with the tube adjacent said closed end of the body; a radiator; a pipe communicating with said chamber and with said radiator, above the water-level thereof, and carrying a suction-opening valve; and a second pipe communicating with said tube 70 and with said intake-manifold.

4. In an automobile, the combination, with the intake and exhaust manifolds of the engine, of a superheater, comprising a hollow 85 body projecting into the exhaust-manifold and closed at the end thereof interior of the exhaust-manifold, and an open-ended tube carried within said body and spaced from the side wall and said closed end thereof, forming a superheating chamber between 90 said tube and said body communicating with the tube adjacent said closed end of the body; a source of supply of liquid fuel; a pipe communicating with said source of supply and with said chamber; and a second 95 pipe communicating with said tube and with said intake-manifold.

5. In an automobile, the combination, with the intake and exhaust manifolds of the engine, of a superheater, comprising a hollow 100 body projecting into the exhaust-manifold and closed at the end thereof interior of the exhaust-manifold, and an open-ended tube carried within said body and spaced from the side wall and said closed end thereof, 105 forming a superheating chamber between said tube and said body communicating with the tube adjacent said closed end of the body; a radiator; a pipe communicating with said chamber and with said radiator, 110 above the water-level thereof; a second pipe communicating with said tube and with said intake-manifold; a source of liquid-fuel supply; and a third pipe communicating with said source of supply and with said chamber. 115

In testimony whereof, I affix my signature in the presence of two witnesses.
